UNITED STATES PATENT OFFICE.

MILTON H. ZIEGLER, OF AKRON, OHIO.

WEATHER STRIP.

Application filed October 15, 1923. Serial No. 668,735.

To all whom it may concern:

Be it known that I, MILTON H. ZIEGLER, a citizen of the United States of America, residing at Akron, in the county of Summit 5 and State of Ohio, have invented certain new and useful Improvements in Weather Strips, of which the following is a specification.

The present invention relates generally to 10 weather strips and particularly to weather strips designed for use upon hinged sashes.

The principal object of the invention is to provide weather stripping which will engage the window sill tightly when the sash 15 is closed and which will disengage itself from the sill as the sash is opened.

Another important object of the invention is to provide a weather strip of this nature which is possessed of a simple and efficient 20 construction, one which is reliable in use, comparatively inexpensive to manufacture, readily associated with the ordinary hinged sash, durable, attractive in appearance, and well adapted to the purpose for which it is 25 designed.

With the above and other objects in view as will appear as the description progresses, the invention resides in certain novel features of construction, and in the combination 30 and arrangement of parts as will be hereinafter more fully described and claimed.

In the drawing:

Figure 1 is a front elevation of the weather strip showing the same associated with a 35 window sash and frame.

Figure 2 is a horizontal transverse section taken substantially on the line 2—2 of Figure 1 looking downwardly.

Figure 3 is a vertical section taken substantially on the line 3—3 of Figure 1.

Figure 4 is a detail perspective view of the weather strip,

Figure 5 is a rear elevation of the weather strip,

Figure 6 is a detail perspective showing a section through the weather strip,

Figure 7 is a perspective view of one of the stop elements used in conjunction with 50 the sash and weather strip, and

Figure 8 is an end elevational view of the weather strip.

Referring to the drawing in detail it will be seen that 1 designates the ordinary win-

dow frame and 2 the sill thereof. The sash 55 3 is of conventional construction and hinged to the frame as indicated at 4.

The weather strip includes a fixed leaf A and a hinged leaf B. The fixed leaf A is in the form of a bar provided with an overhanging extension or depending longitudinal flange 5. This fixed leaf is secured to the bottom of the sash 3. The leaf B is in the form of a bar having its upper edge beveled and hinges 6 are attached thereto 60 having each one of its leaves engaged with the bevel end or edge of the leaf B. The other leaf of the hinges are secured to the rear face of the fixed leaf A. The free end or edge of the leaf B is provided with a 65 strip 7 of suitable weatherproof material. When the leaf B is extended so that its rear face is in the same plane with the rear face of the leaf A, the strip 7 will extend below the bottom edge of the sash 3. Suitable 70 means 8 is provided on the rear faces of the leaves A and B for holding the leaf B in angular relation to the leaf A, the normal position of the parts being indicated to advantage in Figures 4 and 5. By referring 75 to Figure 3, it will be seen that excessive accidental upward swinging of the leaf B will be prevented by the overhanging extension or depending flange 5 of the leaf A. This means 8 preferably includes a resilient wire 80 fixed to the leaves by means of staples 9. The wire spring 8 is preferably disposed obliquely of and on the inner sides of the leaves A and B, and the intermediate portion of the said spring is preferably countersunk in the inner faces of the leaves or positioned in co-extensive oblique grooves 85 90 11 of the latter, whereby the major portion of the spring may be made straight and be protected against damage as shown and yet 95 normally yieldingly maintain leaf B in an outwardly and upwardly swung inoperative position.

The sill 2 of the frame 1 is provided with a stop 10 of L-shaped structure and adapted 100 to be engaged by the hinged leaf B as the sash is swung to a closed position whereby the leaf B will be moved so as to swing into a position to force the strip 7 thereon into a firm and tight engagement with the upper surface of the sill. When the sash is swung to an open position it will be seen that the hinge leaf B will become disengaged from 105

the stop and that the means 8 will move the leaf B so that its strip 7 is raised from out of engagement with the sill.

It is evident that this weather stripping may be used upon doors or upon any swinging member where desired. Although I have described my invention with a certain degree of particularity, it is evident that changes in the details of construction, and 10 in the combination and arrangement of parts may be made without departing from the spirit of the invention as hereinafter claimed:

Having thus described my invention, 15 what I claim as new, is:

In a weather strip, an upper leaf having a depending longitudinal flange on the outer lower corner thereof, hinges, a flat lower leaf having its upper portion attached to 20 the lower portion of the upper leaf by said hinges so that the upper portion of the

lower leaf is normally in spaced relation to and disposed inwardly of said longitudinal flange and whereby the lower leaf may swing vertically relative to the upper leaf, 25 said flange of the upper leaf depending below the upper edge of said lower leaf, and spring means to normally yieldingly maintain the leaves in an angular relation to each other with the lower leaf inclined outwardly, said spring means embodying a piece of resilient wire with a straight intermediate major portion extending obliquely across the inner surfaces of the leaves, said 30 leaves having flat inner surfaces and having oblique co-extensive grooves formed therein in which the straight major portion of the spring is disposed, and means securing said spring to said leaves.

In testimony whereof I affix my signature.

MILTON H. ZIEGLER.
